Attorney

UNITED STATES PATENT OFFICE.

FRANK C. STOWELL, OF MEDFORD, MASSACHUSETTS.

RAIL-FASTENING.

1,367,897.

Specification of Letters Patent.

Patented Feb. 8, 1921.

Application filed July 26, 1918. Serial No. 246,837.

To all whom it may concern:

Be it known that I, FRANK C. STOWELL, a citizen of the United States, residing at Medford, county of Middlesex, Commonwealth of Massachusetts, have invented certain new and useful Improvements in Rail-Fastenings, of which the following is a specification.

The subject matter of my present invention while applicable both in whole and in part to other uses is of most immediate importance with relation to rail fastenings. Rails laid with the usual spikes and tie plates have been subject to a constant loosening constituting a considerable element of trouble and expense in the upkeep of the track and also an element of danger wherever it is of sudden development.

In discussing my invention therefore I shall more particularly refer to its direct application to this problem and to its embodiment in elements adapted to take the place of the usual spikes and rail plates, as such an application of my invention affords a more practical illustrative embodiment of the principles involved.

In spite of the various inventions intended to supplant the familiar square driven track spike, and in spite of its universal tendency to continuously work out under the vertical play of the rails following the passage of the rolling load, that form of fastening still remains in principal service on most roads. This has necessitated frequent redriving of the spikes to properly reseat them and to secure the rails. Most of the devices provide for overcoming this difficulty, notably screw spikes, have not proven sufficiently better to warrant their greatly increased cost.

It is the object of my invention to provide a lock spike and a lock plate readily substitutable for the spikes and tie plates now in use in substantial conformity to the practice in laying rails and capable of production and use at no material increase in cost over the old standard form mentioned above.

The vertical tendency or play of a rail is a factor apparently unavoidable and the pull exerted by the rail in such a movement on any fastening is powerful and persistent. My invention contemplates the utilization of other components of play of the rail for the purpose of keeping the fastening element in place. To this end I provide my

spike with a bearing or shoulder adapted to be introduced beneath the rail directly or indirectly in such a way as to receive the weight of the rolling load and thus make 60 the component of compression which is so intimately related with the reverse movement on return after the load has passed, serve the purpose of seating the fastening securely each time. 65

The construction and operation of my invention will be more fully described in detail in the specification which follows, and is illustrated in the drawings, in which like characters are employed for reference to the 70 specification. In the drawings:

Figure 1 is a partial section through a rail and tie and illustrating one form of my invention in which the spike is adapted to directly engage the lock plate. 75

Fig. 2 is a similar view illustrating a modification in which the spike directly engages the base of the rail, and

Figs. 3 and 4 are detail views on approximately the lines 3—3 and 4—4, respectively, 80 of Figs. 1 and 2.

I have indicated at 1 a tie of usual construction, at 2 a lock tie plate superposed thereon, and at 3 a rail, the base of which rests squarely upon the tie plate between opposed shoulders 4—4 formed on said plate transversely thereof. 85

In the form illustrated in Fig. 1, the track spike is adapted to engage the under face of the tie plate and in Fig. 2 it directly 90 engages the base of the rail. In both forms, the weight of the rolling load on the track acting through the rail and tie plate, and which in all previous forms of rail fastenings has been a continually operating factor to cause the spikes to work out of the tie, is utilized to permanently hold the spike in position. In a word, my spike is held in position by the very forces which withdraw other forms of spike. 95

In Figs. 1 and 2 a cylindrical spike is illustrated, the rounded body portion thereof being indicated at 5. The spike 5 has a hooked head 6 which when in position engages the rail base in the usual manner and is surmounted by a squared head portion 7 which receives the driving blows of the spiking hammer and also provides a wrench hold whereby the spike may be turned into locking position after it has 110 been driven.

Attached to or forming a part of the cy-

cylindrical body portion of the spike is a horizontally disposed locking projection or lug 8. This lug is located at an appropriate distance below the hook head 6, according to 5 whether the spike is to be located under the tie plate 2 as shown in Fig. 1, or under the rail base as shown in Fig. 2.

The tie plates used in connection with my invention are provided with cylindrical holes 9 through the shoulders 4 and of a size 10 to receive the cylindrical body portion of the spike and with extensions of these holes 9, indicated at 10, and constituting passages for the lugs 8 of the same contour but 15 slightly larger than the lugs. The lugs 8 and passages 10 are so located relatively to each other and to the spike head that when the spike is driven the lug will just clear the edge of the rail base and will pass into and 20 through the extension 10, the relation being such that when the upper face of the lug 8 has cleared either the base of the tie plate or the base of the rail, according to which is 25 to be locked by direct engagement with the lug, and has therefore reached its approximate plane of locking engagement, the hook head 6 of the spike will engage the rail base.

After the spike has been driven home, it 30 is given substantially a quarter turn by engaging the wrench hold portion 7 thereof with a suitable wrench. This partial revolution swings the hook head 6 of the spike over the rail base and carries the lug 8 into a position in which it will engage either the 35 under face of the tie plate or the rail base, according to its location along the body portion of the spike. The spike is now locked and the weight of the rolling loads, instead 40 of tending to withdraw the spike as in all previous forms, actually increases the permanence of the locking engagement.

When it is desired to withdraw the spike, the squared portion 7 thereof is engaged and the spike turned until the lug 8 registers 45 with the passage 10, whereupon the usual claw bar is inserted beneath the hook head 6 and the spike is drawn.

In order to facilitate entrance of the lug 8 into the passage 10 through the tie plate the 50 under face of the lug is preferably rounded slightly toward the bottom as indicated at 8', so that in driving should the spike happen not to be exactly concentric with the spike hole 9, this tapering portion of the lug 55 will enter opening 10 and wedge or cam the spike into position when driven. This rounded tapering surface of the lug has the additional advantage of permitting the spike to be more easily twisted when it is 60 embedded in the tie. The leading portion of the lug is therefore a rounded tapering surface, but in order to hold the lug in its opening and prevent it from twisting back to original position after a load has passed, the 65 following end of the lug terminates abruptly

in a shoulder 8" adapted to resist any backing-out tendency of the spike under the vertical movement of the rail.

The distance of the flat top engaging surface 8" of the lug from the bottom of the 70 spike head may vary according to individual preference and requirements. Under some conditions, it may be considered preferable to have the arrangement such that when the lug is in locking contact with the base of 75 the tie plate or the base of the rail, as the case may be, the spike head will at the same time be in actual contact with the upper face of the rail base. Other conditions might require that at such time there should be some 80 slight space between the spike head and the rail base to allow for a certain amount of vertical play of the rail before it actually contacts with the spike head. This allowance for play need be only very slight, and 85 in practice, would probably not exceed $\frac{1}{16}$ to $\frac{3}{32}$ of an inch.

From the foregoing description taken in connection with the drawings, it will be apparent that the spike is locked in position 90 by the very forces which have heretofore operated to withdraw the spike. It has been established that the ordinary driven spike, and the screw spike which has been used in some localities in place of the ordinary 95 driven spike, are withdrawn by the vertical movement of the rail under the weight of the rolling load, and although this movement is very slight, yet because the action is repeated indefinitely the spike is gradually 100 withdraw from the tie.

With my spike and tie plate the tendency of the spike to draw out under the movement of the rail is met by the rail itself and the spike is immediately returned. The spike 105 therefore never gets the first start out, which start causes the ordinary spike to gradually withdraw from the tie, but on the contrary the spike is actually driven down into the tie by the depressing rail. This not only 110 prevents the spike becoming loose in the spike hole but materially helps resist the tendency of the rail and tie plate to sink into the tie.

Various modifications in the form and 115 construction of my device may obviously be resorted to all without departing from the spirit of my invention if within the limits of the appended claims.

What I therefore claim and desire to secure by Letters Patent is:

1. In combination, a rail, a tie, and a tie lock plate having a hole therein and an extension of said hole, a spike adapted to enter said hole and having a lug formed 125 with a tapered under face, a flat locking face, and an abrupt shoulder at its following end and adapted to enter the extension of said hole, said spike rotatable to position said lug in spike-anchoring relation to 130

said tie plate and rail, and having a rail anchoring head adapted for engagement with the upper face of the rail base, and a combination driving and wrench-hold portion on said spike surmounting said rail anchoring portion.

2. In a rail fastening, a tie plate having a hole therein, a track spike comprising a rotatable shank adapted to aline with said 10 hole and having an anchoring lug provided with a rounded leading portion adapted to engage a wall of the hole and cam the spike into said hole should the alinement of hole and shank be inaccurate, and a rail engaging 15 head on said spike above and spaced from said lug.

3. In a rail fastening, a tie plate having a hole therein, a track spike comprising a rotatable shank adapted to aline with said 20 hole and having an anchoring lug provided with a tapered leading portion adapted to engage a wall of the hole and cam the spike into said hole should the alinement of hole and shank be inaccurate and having an 25 abrupt shoulder at its following end adapted to prevent the spike backin' out of the

hole under the play of the rail, and a rail engaging head on said spike above and spaced from said lug.

4. In a rail fastening, a tie plate having 30 a hole therein and having an extension of said hole, a track spike comprising a rotatable shank adapted to aline with said hole and having an anchoring lug adapted to enter said hole extension, said lug having 35 a rounded leading portion adapted to engage a wall of said hole extension and cam the spike into said hole should the alinement of hole and shank be inaccurate and having an abrupt shoulder at its following 40 end adapted to prevent the spike backing out of the hole under the play of the rail, a rail engaging head on said spike above and spaced from said lug, and a combination driving and wrench-hold portion sur- 45 mounting said head.

In testimony whereof I affix my signature in presence of two witnesses.

FRANK C. STOWELL.
